UNITED STATES PATENT OFFICE.

CARL G. BERGMANN, OF CHICAGO, ILLINOIS.

ARCH SUPPORT.

Application filed May 31, 1924. Serial No. 717,180.

This invention relates to an arch support and has for its primary object the construction of an arch support which will positively correct any deformity of the arch.

- 5 An object of the invention is the construction of an arch support that in its use will subject the arch portion of the foot to a rolling, yieldable action in a predetermined direction.
- 10 A feature of my invention is the construction of a body and arrangement of elastic so that the arch bones and heel bone will be rolled and massaged in a predetermined direction so that the weight of the body may be properly carried on these joints.

Besides the above my invention is distinguished in the construction of an appliance that does not have any hard or resilient material to act as a support and which will not subject the wearer to any inconvenience whatsoever.

20 With these and other objects in view the invention will be better understood from the following detailed description taken in connection with the accompanying drawing wherein:

Fig. 1 is a top plan view showing the support or appliance in use.

Fig. 2 is a plan view detached.

30 Fig. 3 is a sectional view on the line 3—3 of Fig. 2.

Fig. 4 is a sectional view on the line 4—4 of Fig. 2.

35 Again referring to the drawing illustrating one of the many constructions of my invention the numeral 1 designates a body of the support constructed from flexible material in this particular instance and of loop shaped formation so that the body may be slipped over the toes and into position to encircle the arch portion of the foot. This body is provided with an extension 2 to which

elastic band 3 is attached. This elastic band 3 is adapted to be passed around the ankle of the foot as shown in Fig. 1 then under 45 the arch to position and then secured to the body by the snap fasteners 4.

From the foregoing description taken in connection with the accompanying drawing it will be apparent that in a very simple 50 manner the appliance is readily attached to the foot and when in position will subject the arch portion of the foot to a rolling massaging action which in time will cause the arch to assume its natural position. It 55 will also be noted that the foot is not subject to the inconvenience of acting upon projections or other rigid or semi-rigid members.

It is, of course, to be understood that the 60 body portion may be constructed from various materials and given other shapes than illustrated and same may be subject to resilient action in various other manners than by the use of a band, therefore, I do not desire to be limited in any manner except as 65 set forth in the claim hereunto appended.

Having thus described my invention what I claim is:

An arch support comprising a flexible loop 70 shaped body adapted to embrace the arch portion of the foot, an extension on the body disposed at an acute angle thereto, an elastic strip having one end secured to the body at the outer end of the extension, and having 75 its other end adapted to be passed around the ankle and arranged in crossed relation with the extension at a point above the instep with its normally free end passed around beneath the arch of the foot and detachably 80 connected to one side of the body.

In testimony whereof I affix my signature.

CARL G. BERGMANN.
